Attorney.

UNITED STATES PATENT OFFICE.

HENRY M. SIEGEL, OF MALDEN, MASSACHUSETTS.

HAIR WAVER.

Application filed March 18, 1924. Serial No. 699,981.

To all whom it may concern:

Be it known that I, HENRY M. SIEGEL, a citizen of the United States, residing at Malden, in the county of Middlesex, State of 5 Massachusetts, have invented a certain new and useful Improvement in Hair Wavers, of which the following is a specification, reference being had therein to the accompanying drawings.

- 10 The present invention has relation to hair-wavers on the order of that of my prior Letters Patent No. 1,385,797 granted July 26, 1921. Like the invention of the said Letters Patent, it comprises a novel and 15 improved means for imparting to the hair of the human head waves or undulations, on the order of what commonly is known as a "Marcel wave." As in the case of the device of the said Letters Patent the purpose 20 of the new form of device constituting the present invention is to enable the user to impart the said undulations without the employment of a curling iron, or other application of heat, such application tending to 25 injure the quality of the hair, and involving the risk of serious damage thereto. As also in the case of the device of the said Letters Patent, the present device has been invented with a view to enabling the user 30 to wave hair successfully, even though not possessed of the high degree of skill and manual dexterity required for successful use of heated appliances, and without the assistance of another person; as well as to 35 leave the user's hands free for other employment during the time while the said bends or undulations are becoming impressed upon the hair, or, as it is usually expressed, while the wave is becoming set.
- 40 The device of the prior Letters Patent comprises a body-portion, a transverse series of teeth at one end thereof to engage a lock of hair adjacent the scalp of the head upon which the device is employed, a double 45 series of oppositely disposed cleats about which the hair may be looped in sinuous manner in an alternating succession, and a retaining finger at the other end to retain the free end of said lock of hair.
- 50 The present invention consists in a novel and improved device designed for the same purposes as the device of the prior Letters Patent, and having essentially the same capabilities, but simpler, smaller, and more compact in its construction, more comfort-

able and convenient while being worn upon the head.

An illustrative embodiment of the invention is shown in the accompanying drawings, in which, 60

Fig. 1 is a perspective view of a hair-waver made in accordance with the present invention.

Fig. 2 is a view thereof in section on line 2—2 of Fig. 1. 65

Fig. 3 is a view in section on line 3—3 of Fig. 1.

Figs. 4, 5 and 6 show the device in plan view, and also a lock of hair, illustrating at different stages one method of winding 70 the lock onto the device.

Having reference to the drawings,—

The hair-waver is made of any suitable light and elastic material, such as celluloid, metal, or other substances. Fundamentally, 75 its form and function are those of a cleat, on which a lock of hair is wound tightly in figure 8 fashion and secured until such lock has acquired a sufficient degree of "set," in the desired undulant curvature. It comprises, as shown, two oppositely extending arms 1, 1, which act to hold the turns of hair in the desired figure 8 shape, as will be more fully described. At right angles to the general direction of extent of the said arms 1, 1, are two projections 2, 2, extending side by side, which will for convenience be termed horns, the said projections or horns being separated from each other by a deep cleft 3 which extends inward to and 80 beyond the middle line of the hair waver. The cleft 3 is provided to receive the lock of hair which is to be operated upon. The portion of such lock which is next the scalp is entered in such cleft as the first step in employing the device. The horns 2, 2, flare apart to a certain extent at their extremities, which are rounded off as shown, to facilitate the entry of the hair into the cleft 3. 85

A hook 4 is provided on the opposite side of the device from the horns 2, 2, and cleft 3, such hook being constituted by the recurved outer end-portion of an arm extending from the body of the device at right angles to the direction of extent of the arms 1, 1. The said hook is adapted to hold the terminal end of the lock of hair firmly after the whole lock has been wound in place upon the device. The bent-back portion of the hook 4 is depressed into close proximity 100

105

110

with its shank, and is made with considerable breadth, to hold said terminal portion by a wedging or pinching action.

The whole device is made slightly concave in both longitudinal and transverse directions, so as to conform to the shape of the head, and lie flat thereon.

In use, the lock of hair to be waved is dampened with water or any other suitable medium, and after being drawn tight, is entered in the cleft 3 while the hair waver is held with its concave side toward the scalp. The device is pushed along the lock of hair into close proximity to the scalp, and the lock is wound back and forth around the oppositely-extending arms 1, 1, in figure 8 fashion as shown in Figs. 4, 5, and 6 until practically the full length thereof has been thus applied. Thereupon the terminal end 20 of the lock is wrapped two or three turns around the stem of the hook 4 and secured by wedging it within the said hook. The device is left in place until the hair dries, and as much longer as is practicable, as the 25 lasting qualities of the wave are in direct proportion to the length of time the undula-

tions or turns are allowed to set, or remain undisturbed upon the device. Thereafter, the end of the lock of hair is disengaged from the retaining hook 4, and the lock is 30 unwound from the arms 1, 1, and the device removed.

Preferably the horns 2, 2, are re-curved, as shown, forming recesses between them and the arms 1, 1, for occupancy by the 35 successive turns of the lock of hair. The said recesses and the recurved horns accommodate the said turns of the lock, and retain them in place effectively.

What is claimed as the invention is:—

The improved hair-waving device comprising a pair of opposite arms upon which a lock of hair may be wound in figure 8 fashion, a pair of horns projecting transversely with relation to the direction of extent of the said arms and separated from each other by a deep cleft, and a stem with retaining hook for securing the end of said lock at the opposite side of the device from the said horns.

HENRY M. SIEGEL
